STEAM-WATER HEATER

Louis M. Puster, Knoxville, Tenn., assignor to
 Robertshaw-Fulton Controls Company, Knoxville, Tenn., a corporation of Delaware

Application October 23, 1947, Serial No. 781,646

3 Claims. (Cl. 261—39)

1

This invention relates to water heaters, and more particularly to water heaters wherein the heating of the water is effected by admixture with steam.

Water heaters have heretofore been proposed wherein steam is injected into the water, but heaters of this character are objectionable for many uses, particularly because of the noise engendered during condensation of steam in water. It is an object of this invention to provide an improved water heater which overcomes these objections by injecting the water into the steam.

Another object of this invention is to provide an improved device of the type characterized wherein the pressure of the incoming steam is maintained at a value lower than the pressure of the water to be heated so as to facilitate the injection of the water into the steam.

Another object of this invention is to provide an improved device of the type characterized wherein the pressure of the incoming water pre-determines the pressure of the incoming steam so as to maintain a constant differential therebetween irrespective of variations in the pressure of the water.

Another object of this invention is to provide an improved device of the type characterized wherein the water is injected into the steam in fine streams or in the form of a spray so as to facilitate intimate intermixture of the water and steam and thereby obtain a mixture the temperature of which is substantially uniform throughout without need for using other provisions for effecting intimate intermixture.

Another object of this invention is to provide an improved device of the type characterized which provides a sufficient storage space for the heated water so that the heated water may be automatically maintained at an approximately constant level.

Another object of this invention is to provide an improved device of the type characterized wherein the level of the heated water may be used as a control for the admission of cold water.

Another object of this invention is to provide an improved device of the type characterized wherein the stored water is maintained at a predetermined temperature higher than that desired at the point of discharge and wherein the discharge temperature is obtained by admixture of cold water with the heated water before delivery to the point of discharge.

Another object of this invention is to provide an improved device of the type last characterized wherein the proportioning of the hot water and

2

the cold water to obtain the desired discharge temperature is automatically controlled from the temperature of the mixture.

Another object of this invention is to provide an improved device of the type last characterized wherein the volume of cold water admitted to the mixture is varied with variations in the pressure of the hot water.

Another object of this invention is to provide an improved device of the type characterized wherein a predetermined discharge temperature is maintained irrespective of variations in the volume of discharge.

Another object of this invention is to provide an improved device of the type characterized wherein the temperature of the heated water is controlled by variations in the level thereof.

Another object of this invention is to provide an improved device of the type characterized wherein the desired temperature of the mixture is automatically maintained by controlling the inflow of cold water while automatically proportioning the amount of cold water injected into the steam and the amount of cold water injected into the heated mixture.

Another object of this invention is to provide an improved device of the type characterized which includes provisions for readily adjusting the controls.

Another object of this invention is to provide an improved device of the type characterized which is simple in construction, composed of parts that are inexpensive to fabricate and assemble, and highly efficient in operation.

Other objects will appear as the description of the invention proceeds.

The invention is capable of receiving a variety of mechanical expressions only two of which are illustrated on the accompanying drawings and it is therefore to be expressly understood that the drawings are for purposes of illustration only, and are not to be construed as definitions of the limits of the invention, reference being had to the appended claims for that purpose.

Referring in detail to the accompanying drawings,

Fig. 1 is a somewhat schematic elevation, partly in section, of an embodiment of the present invention;

Fig. 2 is an enlarged cross sectional detail of one of the controls; and

Fig. 3 is a schematic elevation, partly in section, of an alternative embodiment of the present invention.

55 In the form shown, 10 designates a hot water

tank or other suitable container, of any appropriate size and construction, closed at one end by a cover 11 suitably secured thereto as by bolts or screws 12. Cover 11 has an opening 13 therethrough in which is secured the outlet of a steam inlet line or conduit 14 of any suitable size and construction and shown as having therein a check valve 15. The opposite end of the container 10 is also provided with an opening 16 through which extends into the interior of the container, preferably coaxially therewith, and to a point near to the outlet of the steam line, the outlet end of a cold water inlet line or conduit 17 which terminates in a nozzle 18 of any suitable construction for delivering fine jets or a spray of water into the steam admitted to the container 10 from steam line 14.

In order that the pressure of the steam admitted to the container 10 shall always be predeterminedly lower than the pressure of the water admitted to said container, irrespective of variations in the water pressure, means are provided for maintaining a predetermined differential in pressure between the pressure of the water and the pressure of the steam. To this end, the cold water inlet line 17 includes at any suitable portion thereof a T coupling 19 to which is secured by a suitable coupling 20 a conduit 21, which may be flexible or rigid, leading to a pressure responsive valve mechanism whose housing 22 is suitably connected into the steam line 14. As shown in detail in Fig. 2, conduit 21, at its end opposite coupling 20, has its end secured in an opening in a cap 23 threadedly mounted on the valve housing 22. Mounted interiorly of said housing in communication with said conduit 21 is an expandable and collapsible chamber 24, here shown as provided by an expandable and collapsible corrugated tubular wall or bellows 25 hermetically sealed to a ring 26, that is clamped between the threaded cap 23 and the body of the valve housing 22, and to a movable end wall 27. Suitably attached to end wall 27 is a valve stem 28 which in turn is suitably secured to a valve member 29 adapted to cooperate with a port 30 provided in a partition 31 interiorly of the valve housing 22. With the valve in the position shown in Fig. 2, the steam inlet pipe 14 is connected to the left-hand side of the housing as indicated by the arrow. Valve member 29 and the movable end wall 27 of bellows 25 preferably have the same effective area so as to balance the forces exerted on the valve member 29 and end wall 27 by the supply steam and insure that movement of the valve member 29 is independent of the supply steam pressure. Housing 22 carries a second threaded cap 32 provided with a threaded opening 33 in which is adjustably mounted a screw 34 that terminates in a spring seat 35. Interposed between the spring seat 35 and the valve member 29 is a spring 36 acting in opposition to the pressure in chamber 24.

The pressure in the inlet water line 17 is therefore transmitted through conduit 21 to chamber 24 to open the valve member 29 in opposition to the tension of the spring 36 and to the back pressure in pipe 14 acting upon valve member 29, and by appropriately adjusting the screw 34 the tension of said spring may be set to maintain a predetermined difference in pressure between the pressure of the water in pipe 17 acting on bellows 24 and the back pressure of the steam acting on valve 29. Hence, irrespective of variations of pressure in the water, the steam pressure admitted to the container 10 may be maintained

at a constant differential so that the jets or spray of water from the nozzle 18 may readily penetrate the incoming steam and by intimate intermixiture therewith effect the desired heating of the water.

Formed on or suitably secured to the container 10 is a lateral tubular extension 38 in open communication with the interior of the container 10. Secured in any suitable way in the open end of said extension 38, as by the nut 39, is a bulb 40 that is in communication through a suitable conduit 41, which may be flexible or rigid, with an expandable and collapsible chamber at 42, said chamber having a movable wall connected by valve stem 43 to a valve member 44 disposed in a valve housing 45 suitably connected at any suitable point into the cold water inlet line 17. The construction of thermostatically operated valve here employed may be the same as, and has been illustrated as the same as, that employed in the hot water outlet line hereinafter described in greater detail except that valve member 44 is reverse acting and valve member 61 is direct acting. The thermostat 40, 41, 42, so provided is charged with any suitable thermostatic fluid, and an adjustable nut 46 cooperating with a spring opposing expansion of said chamber, as hereinafter explained in conjunction with the valve in the hot water outlet line, provides for the adjustment of the temperature at which the thermostat so provided responds to effect opening and closing of the valve member 44.

The water level in the container is normally such that the bulb 40 is covered by the water as shown in Fig. 1. When water is withdrawn from the container the water level is lowered so that the bulb 40 becomes exposed to the temperature of the steam, whereupon the thermostat 40, 41, 42, by expansion or volatilization of its charge, operates to open the then closed valve member 44 and admit cold water to the nozzle 18. The water sprayed into the steam is heated by the steam, and if the heated water is not withdrawn as rapidly as cold water is admitted through the nozzle 18 the heated water accumulates in the container 10 until it rises to approximately the level shown in Fig. 1 so as to cover the bulb 40, thereby shielding the bulb from the temperature of the steam. The lower temperature to which the bulb 40 is now subjected results in a contraction or condensation of the charge in the thermostat 40, 41, 42 with resultant closure of the valve member 44. As soon as water is again withdrawn from the container 10, however, the water level is again lowered so as to reexpose the bulb 40 to the temperature of the steam, whereupon the valve member 44 is again opened to effect injection of the cold water through the nozzle 18 into the steam. Thus the cycle is repeated each time withdrawal of water changes the level to expose the bulb 40 to the temperature of the steam. By appropriate adjustment of the nut 46 the temperatures at which the valve member 44 is opened and closed may be nicely predetermined.

Also in communication with the container 10 is any suitable hot water outlet line or conduit 48 by which hot water may be withdrawn from said container. In the embodiment of the invention illustrated it is contemplated that the water in the container 10 will be at a temperature substantially above that at which it is desired that the heated water be discharged, and to reduce the temperature of the water at the discharge to the desired temperature for use,

cold water is mixed with the hot water leaving the container 10. To this end, the cold water inlet line 11 includes at any suitable point, preferably on the inlet side of a check valve 41, a T coupling 49 with which communicates a cold water conduit 50 that is in communication, as by means of a T coupling 51, with the hot water outlet line 48, conduit 50 preferably including a check valve 52 to prevent reverse flow of the water. In order that the volume of cold water admitted to the hot water line 48 shall be properly proportioned to the hot water notwithstanding variations in pressure in the hot water line 48, conduit 50 preferably has interposed therein a pressure responsive valve 53, which may be of identical construction with the valve at 22, and including an expansible and collapsible chamber to which the valve member is attached with the chamber in communication with the hot water line 48 through a suitable conduit 54, which may be flexible or rigid, leading to a T coupling 55 interposed at a suitable point in the hot water line. The expansible and collapsible chamber at 53 and the valve member to which it is attached operate in opposition to a spring and to back pressure from T 51, as illustrated in Fig. 2, and the tension of the spring may be adjusted by manipulation of a screw 56 comparable to the screw 34. Thereby variations of pressure in the hot water line 48 will operate the valve at 53 to vary the flow of cold water so as to avoid fluctuations in the temperature of the mixture due to variations in pressure in the hot water line 48. When the pressure in hot water line 48 remains constant and valve member 61 is throttled down by reason of high temperatures at bulb 72 the pressure in coupling 51 which is exerted on the discharge side of the valve member of valve 53 is decreased and valve 53 is opened to admit cold water to the mixture to cool the same to the desired temperature.

To maintain a predetermined temperature of the mixture of hot and cold water delivered to the outlet 58, a thermostatically operated valve controlled by the temperature of the mixture is also provided to vary the proportions of hot and cold water flowing to the outlet 58. Said thermostatically operated valve may be used to control the admission of either the hot water or the cold water, but as shown it is disposed in the hot water line 48. When this valve is placed in the cold water line valve 53 must be placed in the hot water line. As illustrated, a suitable valve housing 59 is interposed at any suitable point in the hot water line 48, preferably on the outlet side of a check valve 60, and has therein a valve member 61 for cooperation with a valve port 62 suitably provided in a partition 63 interiorly of said valve housing 59. Valve member 61 is connected by a valve stem 64 with the movable end wall 65 of an expansible and collapsible chamber 66, here shown as having an inner flexible wall provided by an expansible and collapsible corrugated tubular member or bellows 67 hermetically sealed at its opposite ends to said movable end wall 65 and to a stationary ring 68 secured to or formed as a part of the frame 69. Chamber 66 is completed by an exterior cup-shaped wall 70 hermetically secured to the ring 68 and surrounding the bellows 67. Sealed into said cup-shaped wall 70 is a suitable conduit 71 which may be rigid or flexible, leading to a bulb 72 mounted in any suitable way, as by a nut 73, in an aperture in a housing 74 through which the mixture of hot and cold water flows. Threadedly mounted in the ring 68 is a nut 75 which

provides a spring seat for a coil spring 76 interposed between said nut and the movable end wall 65. By adjustment of said nut 75 the tension of the spring 76 may be varied to predetermine the temperature at which the thermostatic charge, which may be of any suitable character, in the bulb 72, conduit 71 and chamber 66 will respond to the temperature of the mixture flowing through the housing 74.

As illustrated, a manually operable valve 78 is shown on the outlet side of the housing 74 for opening and closing the conduit leading to the outlet 58.

In operation, steam at any suitable pressure is connected through the steam line 14 to the interior of the container 10, while cold water is connected through the cold water line 17 to the temperature responsive valve at 45. Upon withdrawal of water from the container 10 the bulb 40 is exposed, and steam entering the container contacts the bulb 40, and due to the expansion or volatilization of the thermostatic charge in the thermostat 40, 41, 42, valve member 44 is opened to admit the cold water to the nozzle 18. The pressure of the cold water in the conduit 17 is also communicated to the pressure responsive valve at 22 in steam line 14, and under appropriate adjustment of the tension of spring 36 the valve member 29 is opened by the pressure of the cold water to such an amount as to maintain a predetermined differential in the pressure between that of the cold water and that of the steam in chamber 10. Hence a spray of cold water is delivered by the nozzle 18 that readily penetrates the incoming steam and abstracts heat therefrom, falling into the container 10. If the level of the water in the container 10 rises to cover the thermostat bulb 40 the lower temperature of such water causes a contraction or condensation of the charge in the thermostat 40, 41, 42, effecting the closure of the cold water valve, but any withdrawal of hot water which exposes the bulb 40 results in the reopening of the cold water valve at 45 and injection of the cold water into the steam to maintain the supply of hot water.

When water is withdrawn through the outlet conduit 58 the hot water at its relatively high temperature leaves the container 10 through hot water line 48 and becomes mixed in said conduit with cold water delivered through the conduit 50. Any variations in pressure in the line 48 are transmitted through the conduit 54 to the pressure responsive valve at 53 so as to appropriately proportion the pressure of cold water to the pressure of hot water. The mixture of hot and cold water so effected then flows over the bulb 72 whereby the charge in the thermostat 72, 71, 66, responds to the temperature of said mixture to operate the valve member 61 and increase or decrease the flow of hot water as required to maintain a predetermined temperature of water discharged through the outlet 58, the temperature so maintained at the outlet being adjustable by manipulation of the threaded nut 75 to vary the response of thermostat 72, 71, 66 to the temperature of the mixture.

A second embodiment of the present invention is illustrated in Fig. 3. As here shown, a container 80 of any suitable size and construction is closed at one end by a cover 81, attached thereto in any suitable way as by bolts or screws 82. Cover 81 has an aperture 83 in which is suitably secured the outlet end of a cold water line 84, said outlet end being shown as extending coaxially

into the container 80 for a major portion of its length and being closed at its inner end by a plug 85. A suitable portion of the extremity of said inwardly projecting cold water line 84 has suitable apertures 86 of appropriate size to deliver fine jets of water. Also communicating with the end of the container 80 adjacent the cover 81 is a steam inlet line 87 which preferably includes a check valve 88. Interposed in the steam line 87 is a pressure responsive valve 89 in communication through a suitable conduit 90, which may be rigid or flexible, with a T coupling 91 interposed in the cold water line 84, preferably on the outlet side of a check valve 92. Pressure responsive valve 89 with its connections 90, 91 may be of the same construction as the pressure responsive valve 22 shown in Fig. 2, the steam inlet 87 being connected to the left-hand side of the valve housing as shown in this figure and the valve performing the same function of maintaining a predetermined differential in pressure between that of the cold water and that of the steam admitted to the container 80.

As further shown in Fig. 3, the opposite end of the container 80 has suitably attached thereto, as by bolts or screws 93, a housing 94 from which leads an outlet conduit 95 that may include a hand operated valve 96, such as shown at 78 in Fig. 1. Projecting into said housing 94 is a bulb 97 mounted in any suitable way, as by the nut 98, and with which communicates a conduit 99, which may be rigid or flexible, leading to an expansible and collapsible chamber at 100. The thermostat 97, 99, 100 may have any suitable charge and may be of the same construction as the thermostat 72, 71, 66 in Fig. 1. The movable wall of the expansible and collapsible chamber at 100 is connected by a valve stem 101 to a valve member 102 cooperating with a port 103 in any suitable partition 104 provided in the housing 105, and an adjustable nut 106 cooperates with a spring for adjusting the response of the thermostat 97, 99, 100 as in the embodiment of Fig. 1.

In the operation of the embodiment of Fig. 3, steam is admitted to the container 80 through the steam line 87, and cold water is admitted to the container 80 through the cold water line 84, water being injected into the steam in fine jets or in the form of a spray through the apertures 86. As in the embodiment of Fig. 1, pressure responsive valve 89 with its connections 90 and 91 operates to maintain a predetermined differential in pressure between that of the cold water and that of the steam. Cold water may flow as jets from the cold water line throughout the area provided by the apertures 86, but the number of jets exposed to the steam depends on the level of the water in the container 80. The cold water inlet line has a maximum capacity in excess of the capacity for withdrawal of water through the outlet 95 so that heated water may accumulate in the container. As water heated by the jets accumulates in the container 80 it progressively covers the apertures 86, decreasing the amount of cold water that is injected into heat interchanging relationship with the steam and increasing the proportion of cold water that is injected directly into the hot water to lower its temperature until a predetermined temperature is reached as determined by the rate of admission of cold water through the valve at 105 under the control of the thermostat 97, 99, 100 responding to the temperature of the water flowing to the outlet 95 over bulb 97. When water is withdrawn from the container 80 the level therein

is lowered to increase the proportion of the jets delivering into the steam. This water of progressively increasing temperature then reaches the bulb 97 which thereafter responds to the temperature of the water flowing thereto to effect an increase or decrease of the cold water admitted to the container as required by the temperature of the water leaving the container. If the temperature at the bulb 97 increases above that to be maintained at the outlet as determined by the adjustment 106 the charge in the thermostat 97, 99, 100 expands or volatilizes to open the valve member 102 and thereby increase the flow of cold water. If the temperature at the bulb 97 decreases below that to be maintained said thermostat correspondingly closes the valve member 102. Thereby the level of the water in the container 80 is varied by varying the admission of cold water so that the number of apertures through which cold water may be sprayed into the steam and the number of apertures through which cold water is injected directly into the hot water to lower its temperature is automatically adjusted to obtain water at the bulb 97 of predetermined temperature. Thereby a predetermined temperature is maintained at the outlet through varying the inflow of cold water to the container so as to vary the level therein until a balance is reached such that the proportion of cold water delivered directly into the hot water to the proportion of cold water injected into the steam is proper for maintaining the desired temperature.

It will therefore be perceived that by the present invention a hot water heater has been provided wherein the heating of the water is effected by admixture with steam, but as the water is injected into the steam rather than vice versa the noise which characterizes the injection of steam into water has been avoided. By maintaining the pressure of the steam predeterminately lower than that of the water, the water may be injected in fine jets or a spray which penetrates the steam into intimate heat interchanging relationship therewith so that the water is heated with substantial uniformity without the need of any additional provision for effecting mixture.

If, as in the embodiment of Fig. 1, it is desired to maintain the hot water in the container at a temperature above that at which it is to be used, the present invention provides for the reduction of the temperature of the water before discharge by admixture of cold water therewith, the volume of cold water admitted to the mixture being responsive to variations in pressure of the hot water, while the temperature of the mixture is nicely predetermined by varying the portions of hot and cold water intermixed so as to assure the desired temperature at the outlet.

On the other hand, as in the embodiment of Fig. 3, the temperature of the water delivered from the container may be accurately predetermined by varying the volume of cold water admitted to the container, utilizing the level of the water in the container to automatically proportion the amount of cold water injected directly into the hot water to the amount of spray injected into the steam so as to establish a balance which maintains the desired temperature at the outlet. However, while the embodiment of Fig. 3 particularly lends itself to a heater wherein the temperature maintained at the outlet of the container is that at which the hot water is to be used, it will be apparent to those skilled in the art that the embodiment of Fig. 3 may be used

for automatically maintaining the temperature in the container higher than that at which the water is to be used, in which event the delivery from the container may, as in the embodiment of Fig. 1, be connected to a cold water pipe for adding cold water to the hot water for lowering the temperature of the water as used, as by use of a cold water conduit comparable to conduit 50 in Fig. 1, and pressure and temperature responsive valves, such as used at 53 and 59 in Fig. 1, may then be employed for controlling the volumes of hot and cold water intermixed.

While the embodiments of the invention illustrated on the drawings have been described with considerable particularity, it is to be expressly understood that the invention is not limited thereto. As will now be apparent to those skilled in the art, the invention is capable of receiving a variety of mechanical expressions, while changes may be made in the details of construction, arrangement, proportion, sizes, etc., certain features may be used without other features, parts may be replaced by equivalent parts, etc., without departing from the spirit of this invention. Reference is therefore to be had to the appended claims 25 for a definition of the invention.

What is claimed is:

1. In a water heater, in combination with a container for the heated water, a conduit for conveying steam to the interior of the upper portion of said container to form an atmosphere of steam therein, a conduit for conveying cold water to the interior of said container and including an elongated tube apertured to form jets over a substantial portion of the height of said container, said tube being arranged to be immersible at least in part in the water in said container, a pressure reducing valve in said steam line, means responsive to the pressure of the water in said water line for operating said reducing valve to maintain the pressure of said steam atmosphere predeterminedly lower than the pressure of said water, a valve in said water conduit, and a thermostat operatively connected to said last named valve and subjected to the temperature of the 45 heated water in said container for controlling the inflow of water and varying the level of the water in said container to proportion the jets delivering into said atmosphere of steam to the jets delivering into the water below the level thereof to maintain a substantially uniform temperature of said heated water.

2. In a water heater, in combination with a container for the heated water, a conduit for conveying steam to the interior of the upper portion of said container to form an atmosphere of steam therein, a conduit for conveying cold water to the interior of said container and including an elongated tube apertured to form jets over a substantial portion of the height of said container, 55 said tube being arranged to be immersible at least in part in the water in said container, a pressure reducing valve in said steam line, means respon-

sive to the pressure of the water in said water line for operating said reducing valve to maintain the pressure of said steam atmosphere predeterminedly lower than the pressure of said water, an outlet conduit in communication with said container, and means for maintaining a substantially uniform predetermined temperature of the water flowing through said outlet including a valve in said water conduit and a thermostat operatively connected to said valve and subjected to the water flowing to said outlet for predeterminedly the volume of water flowing into said container and immersing below the water level in said container so many of said jets that the jets delivering into the atmosphere of steam will in conjunction with the immersed jets establish and maintain a predetermined temperature.

3. In a water heater, in combination with a container for the heated water, a conduit for conveying steam to the interior of the upper portion of said container to form an atmosphere of steam therein, a conduit for conveying cold water to the interior of said container and including an elongated tube apertured to form jets over a substantial portion of the height of said container, said tube being arranged to be immersible at least in part in the water in said container, a pressure reducing valve in said steam line, means responsive to the pressure of the water in said water line for operating said reducing valve to maintain the pressure of said steam atmosphere predeterminedly lower than the pressure of said water, and means for varying the level of the water in said container to vary the number of jets delivering to said atmosphere of steam including a valve in said water conduit and a thermostat subjected to the temperature of the water in said container and operatively connected to said last named valve for respectively increasing and decreasing the inflow of cold water upon increase and decrease of the temperature of the heated water in said container.
